FLAME HARDENING APPARATUS

Albert L. Hartley, Cincinnati, Ohio, assignor to
 The R. K. Le Blond Machine Tool Company,
 Cincinnati, Ohio, a corporation of Delaware

Application November 27, 1942, Serial No. 467,119

5 Claims. (Cl. 266—4)

1

This invention pertains to flame hardening apparatus and is particularly related to such apparatus adapted to the flame hardening of relatively long small diameter holes in work pieces. This invention is specifically adapted to such types of work as hardening the tapered bores in spindles for lathes or the like.

In flame hardening a relatively long small diameter bore in a work piece certain specific problems come about which are not present when exterior surfaces of work are to be flame hardened. One of the most difficult problems involved in the hardening of a hole in a work piece of this character is that of applying a suitable flame hardening torch in the bore so as to uniformly and rapidly heat the internal surface of the bore while at the same time providing suitable discharge passageways in the torch to permit free escape of the burned gases during the flame heating process. It is then the difficult problem of applying the quenching coolant to the work surface substantially instantly after the flame hardening torch has brought the surface to the proper temperature for quenching. This again necessitates the peculiar handling of the flame hardening apparatus in that the flame hardening torch must be rapidly withdrawn from the bore of the work piece and the coolant discharging nozzle promptly inserted therein and coolant applied to the heated surface so as to effect the proper quenching and hardening of the bore in the work piece.

All of these operations must be undertaken in a coordinated and accurately controlled manner so as to permit the proper functioning of the flame hardening process in the bore of the work piece.

Further features and advantages of this invention will appear from the detailed description of the drawings in which:

Figure I is a side elevational view of the bore flame hardening apparatus shown applied to a typical lathe spindle shown in fragmentary section together with additional flame hardening torches applied to completely finish flame hardening the outside diameter at the same time the bore is being hardened.

Figure II is a transverse vertical section on the line II—II of Figure I particularly showing the roller reciprocating slide and actuating air cylinder for alternately presenting the flame hardening torch or the coolant nozzle to the bore to be flame hardened.

Figure III is a front elevational view of the

2

flame hardening apparatus shown on the line III—III in Figure I.

Figure IV is a plan view of the flame hardening burner having a relatively long tapered extension portion for entrance into the bore of the work piece to be flame hardened.

Figure V is an end elevation of the flame hardening burner of Figure IV particularly showing the fluted portion to permit escape of the burned gases during the heating process and which also serves to provide access for the coolant nozzle when presented to the bore upon withdrawal of the flame hardening torch or burner of Figure IV.

Figure VI shows a side elevation of the burner of Figure IV.

Figure VII is a plan view of the coolant nozzle associated with the flame hardening burner which is inserted into the bore of the work piece being flame hardened while at the same time the burner is removed therefrom, so that coolant may be thoroughly distributed in the bore of the work piece without the formation of steam pockets or eddy currents which might otherwise be the case when cooling is undertaken in the presence of the flame hardening burner.

Figure VIII is an end view of the coolant nozzle showing its association with the flame hardening burner.

Figure IX is a side elevation of the coolant nozzle of Figure VII.

Figure X shows the relationship of the exterior flame hardening torches for simultaneously flame hardening the outside tapered portion of the work spindle while the bore is being flame hardened.

Figure XI is a view shown on the line XI—XI of Figure I, of the flame hardening torches surrounding the cylindrical portion of the work spindle for hardening the back portion of the clamping flange of the work spindle simultaneously with the hardening of the bore and exterior tapered surface thereof.

Figure XII is a side view of one of the arcuate flame hardening torches applied to flame hardening the rear portion of the clamping flange of the spindle.

Figure XIII is a section thru one of the flame hardening burners of Figure XI on the line XIII—XIII of said figure.

For exemplary purposes this invention is shown applied to a typical lathe spindle W having the usual relatively long small diameter taper bore 1 which is to be flame hardened so as to prevent damage and scoring of this bore with the insertion or withdrawal of various lathe fixtures such as the centers, collets, etc. The apparatus com-

prises a main body portion 2 which is suitably mounted to a fixed frame 3 of a flame hardening machine (not shown) by appropriate bolts 4. In this frame 2 is slidably mounted a pair of reciprocating carriages 5 and 6 having rollers 7 operating in appropriate slots 8 formed in the frame 2. On the upper carriage 5 is fixed a bracket 9 to which is appropriately fixed a piston rod 10 of a reciprocating gear cylinder 11 appropriately mounted on the surface 12 of the frame 2 by bolts 13 so that reciprocation of the piston rod 10 through the medium of its piston (not shown) in the cylinder 11 effects sliding reciprocation movement of the carriage 5 back and forth with its rollers 7 operating in the slots 8 in the frame 2.

The lower carriage 6 is likewise reciprocated by the cylinder in opposite reciprocatory motion through the medium of a pinion 14 carried on an appropriate stud 15 and which engages a rack 16 on the carriage 5 and a rack 17 on the carriage 6 so that when the carriage 5 is moved to the right, for example, in Figure I the carriage 6 will similarly be moved to the left in this figure. Gear 14 carried on the shaft 15 may be withdrawn from operative position with the racks 16 and 17 or for re-engaging them in different relative positions to effect different relative positioning of carriage 5 with carriage 6, by means of the operating knob 18, Figure II, which is connected to this shaft 15 and which may move it axially to the right to disengage the gear 14 from the racks 16 and 17. Appropriate detent means 19 serves to position the shaft 15 either with gear 14 engaged with the racks 16 and 17 or disengaged therefrom. In the latter case this is desirable when it is not necessary to oppositely reciprocate the carriage 5 with respect to the carriage 6 as in other types of flame hardening operations.

On a bracket 20 fixed to the carriage 5 by appropriate screws 21 are mounted the flame hardening torches 22 of conventional design to which is connected the special flame hardening burner 23 through suitable connections 24. This burner 23 is best shown in Figures IV, V, and VI and comprises a connecting portion 23a having the input line 25 through which enters the mixture of oxygen and acetylene which is conducted through the passageways 26 and 27 to the jet openings 28 as best shown in Figure V. Coolant water enters the portion 23a of the burner 23 through a passageway 29 and through the passageways 30 and 31 and discharging out the passageway 32 outside the bore of the workpiece being hardened. This coolant traversing these passageways is for the purpose of keeping the tapered portion 23b of the flame hardening burner 23 properly cooled during the operation. This coolant, however, is not used for quenching the work surface after it has been brought up to flame hardening temperature. The fluted design of this burner comprises the grooved portions 33, 34, and 35 which serve the dual function of first permitting free escape of the burned gases issuing from the jet openings 28 and also serve as access openings by which the coolant nozzle arrangement of Figures VII, VIII, and IX may be readily entered into the bore of the work piece while at the same time permitting rapid withdrawal of the flame hardening burner from the bore after the work piece has been brought to the proper flame hardening temperature.

This coolant nozzle arrangement is mounted on the lower carriage 6 by means of a bracket 36 connected to it by appropriate screws 37 and hav-

ing mounted on it the mounting flange portions 38 and 39 of the coolant cylinder. In this particular arrangement this coolant nozzle comprises a series of three parallel water tubes 40, 41, and 42, which respectively lie parallel to and in the respective fluted portions 33, 34, and 35 of the flame hardening burner 23 as best seen in Figures III and VIII. These tubes are connected by appropriate portions 43, to a manifold portion 39 having the input passageway 44 by which quenching fluid may be applied to the tubes 40, 41, and 42 which outlets 45 permit the fluid to spray rapidly and without eddy currents or steam pockets being formed upon the work surface having been previously heated by the burner 23.

Thus, referring to Figure I, the operation of this apparatus comprises first presenting the burner 23 as shown in Figure I, igniting the oxy-acetylene mixture coming in through the mixing arrangement and torches 22 and through the fittings 24 into the burner 23 and continuing the heating of the bore 1 of the work spindle W until it has arrived at its flame hardening temperature. Immediately upon arriving at this critical temperature the air cylinder and its piston rod 10 are operated to substantially instantly withdraw the burner 23 telescopically past the coolant nozzle comprising the tubes 40, 41, and 42 which movement, through the medium of the gear 14 and associated racks 16 and 17, causes the nozzle to be immediately inserted into the bore upon full withdrawal of the flame hardening burner 23. Coolant is then instantly turned on through this nozzle to quench the bore of the work piece to flame harden the work in a completely automatic cycle. In this way the escaping gases, during the heating operation may be passed through the fluted portions 33, 34, and 35 of the flame hardening burner 23 and these areas may also be utilized to permit quick entrance of the coolant nozzle into the bore upon withdrawal of the flame hardening burner 23 so that the coolant may be thoroughly distributed in the bore of the work piece to quench it without interference and the creation of eddy currents or steam pockets which would otherwise occur where the flame hardening burner remains in position in the bore during the quenching operation. It is to be further understood, of course, that during both the heating and the quenching operations the work piece W is rotated at an appropriate speed to effect the proper flame hardening of the bore 1.

It is to be further noted that additional flame hardening burners 46 may also be carried on an appropriate bracket 47 fixed to the frame 2 to effect the flame hardening of the outer tapered surface 48 of the spindle W at the same time the bore portion is being hardened if such an arrangement be desired. In this instance four such torches 46 would be utilized as shown in Figure X, each with appropriate mixer tubes 49 connected to torches similar to that of the torch 22. In this case, however, since it is an external surface, the quenching water is caused to play upon the work from appropriate outlet jets 50 after the flame hardening surface has been completed by the jets 51 in the conventional fashion for such type of flame hardening operation.

As may be also noted appropriate burners 52 as shown in Figures XI, XII, and XIII may be utilized to effect the hardening of the rear flange portion 53 of the work spindle W also carried on simultaneously with both the hardening of the bore and of the tapered portion 48 of the work

2,412,383

5

spindle. This arrangement of the burners 52 are formed arcuately so their configuration fits around the work spindle W and the coolant water is applied after the work has been heated to flame hardening temperature by the torches through the medium of water jets in the torch or any other outside means for applying this coolant to the surface 53 after it has been appropriately heated.

Having thus fully set forth and described my invention what I claim as new and desire to secure by United States Letters Patent is:

1. In a flame hardening apparatus, a longitudinally extending flame hardening burner projectable into a bore to be flame hardened in a work piece, a quenching coolant nozzle longitudinally arranged for presentation into said bore of said work piece, movable mounting means for said burner, and movable mounting means for said coolant nozzle, and common means for reciprocating said respective mounting means so as to alternately insert said burner or said nozzle into the bore of said work piece, said burner and nozzle being telescopically inter-related so that said coolant nozzle may be inserted into said bore of said work piece while said burner is being removed therefrom, said telescopic association of said burner and nozzle comprising longitudinally extending passageways in said burner serving to provide escape for the burned gases when said burner is in operation in said bore and further serving to permit said coolant nozzle to be injected into the bore of said work piece while said nozzle is being withdrawn therefrom.

2. In a flame hardening apparatus for hardening an elongated small diameter bore in a work piece, an elongated flame hardening burner, an elongated coolant nozzle, a pair of oppositely reciprocatable slides for alternately or simultaneously presenting said burner and nozzle in the bore of said work piece, rack and pinion means for reciprocating said slides, means for disengaging said rack and pinion means for independent movement of said slides, and longitudinally extending passageways formed on the exterior of said burner for the escape of burned gases during the operation of said burner in said bore and to allow simultaneous insertion of said nozzle and burner in said bore.

3. In a flame hardening apparatus, a longitudinally extending flame hardening burner

6

mounted on a slide for movement into a bore to be flame hardened in a work piece, a quenching coolant nozzle mounted on another slide for presentation into said bore, common rack and pinion actuating means for oppositely reciprocating said slides, longitudinally extending grooves formed in said burner to facilitate disposal of burned gases during the operation of said burner and to at the same time provide passageways for the insertion of said nozzle in said bore during the presence of said burner therein, and means for disengaging said common rack and pinion driving means to allow independent movement of said slides.

4. In a flame hardening apparatus, a main body portion, a pair of slides mounted on said body portion, a flame hardening burner mounted on one of said slides, a quenching coolant nozzle mounted on the other of said slides, disengageable rack and pinion means for simultaneously oppositely reciprocating said slides or to allow independent movement of said slides, passageways formed on said burner to allow escape of burned gases during the operation of said burner in the bore of said work piece, said passageways being arranged to allow said coolant nozzle to be disposed circumferentially about said burner within the confines of the bore of said work piece so that said burner and nozzle may be alternately or simultaneously inserted in said bore by axial movement of said burner and nozzle by said slides.

5. In a flame hardening apparatus, the combination of a main body portion, a pair of slides reciprocatably mounted on said body portion, rack and pinion means for oppositely reciprocating said slides, means for disconnecting said rack and pinion mechanism for independent movement of said slides, a flame hardening burner mounted on one of said slides, a quenching coolant nozzle mounted on the other of said slides, in telescopic relationship with said burner, and passageways formed in said burner extending longitudinally thereof and axially of the bore to be flame hardened in the work piece, said passageways serving to both facilitate disposal of burned gases during the operation of said burner and to allow the simultaneous or independent insertion of said burner and nozzle in said bore of the work piece.

ALBERT L. HARTLEY.
